Primary Examiner — Raphael Barkai(74) *Attorney, Agent, or Firm* — Larry K. Roberts(57) **CLAIM**

The ornamental design for an eyeglass lens, as shown and described.

DESCRIPTION

FIG. 1 is a front perspective environmental view of a pair of eyeglass lenses in accordance with an embodiment of the design;

FIG. 2 is a front perspective view of an eyeglass lens of the embodiment of FIG. 1;

FIG. 3 is a front view of the eyeglass lens of FIG. 2;

FIG. 4 is a rear view of the eyeglass lens of FIG. 2;

FIG. 5 is a left view of the eyeglass lens of FIG. 2, with the right side being a mirror image of the left view;

FIG. 6 is a top view of the eyeglass lens of FIG. 2; and,

FIG. 7 is a bottom view of the eyeglass lens of FIG. 2.

The broken lines shown in FIG. 1 are for illustrative purposes only and form no part of the claimed design.
